[57] CLAIM

The ornamental design for a glove, as shown and described.

DESCRIPTION

FIG. 1 is a front perspective view of a glove showing my new design;

FIG. 2 is a right side perspective view thereof;

FIG. 3 is a left side perspective view thereof;

FIG. 4 is a dorsal view thereof;

FIG. 5 is a top end perspective view thereof;

FIG. 6 is a right side perspective view thereof;

FIG. 7 is a palmar view thereof; and,

FIG. 8 is a bottom end perspective view thereof.

The broken line showing of the human form in FIG. 2 and the wrist strap in FIGS. 1-8 are for illustrative purposes only and form no part of the claimed design.

1 Claim, 2 Drawing Sheets

FIG. 1

FIG. 2
